UNITED STATES PATENT OFFICE.

FRANS SMULDERS, OF ROTTERDAM, NETHERLANDS.

LUFFING-CRANE.

1,096,400.

Specification of Letters Patent. Patented May 12, 1914.

Application filed December 10, 1912. Serial No. 735,905.

To all whom it may concern:

Be it known that I, FRANS SMULDERS, subject of the Queen of the Netherlands, residing at Eendrachtsweg 9, Rotterdam, 5 Netherlands, have invented certain new and useful Improvements in Luffing-Cranes, of which the following is a specification.

It is generally necessary with cranes and especially in sluing floating cranes, that the 10 crane load should itself be deposited on the pontoon or equivalent member which supports the crane. To this end it is necessary in most cases, to luff, or what is the same thing, alter the radius of the crane, together 15 with its load, which adjustment is ordinarily effected by means of a counterweight or luffing screw or equivalent device arranged at the end of the jib opposite to that where the load is applied. The luffing screw 20 should have a length proportional to the length of the jib. The consequence is that the screw frequently has a very great length, so that it is necessary to provide for its mounting and guidance a framework of con- 25 siderable height above the deck of the pontoon. In such cases it is necessary, in conse- 30 quence, for reasons of stability, to increase the size of the pontoon. Moreover, in known arrangements, the load on the jib 35 pivot, comprises, on the one hand, the weight of the raised load augmented by part of the weight of the jib itself and the counter weight, and on the other hand, the force necessary for luffing the jib and its load, which force is often very great.

The present invention has for its object 40 mechanism for adjusting the jibs of sluing cranes, which is particularly applicable to floating cranes, allows of the height of the frame supporting the luffing screw being reduced to about half what it is ordinarily, and obviates any action, on the jib pivot, of the force for luffing the jib and its load.

The accompanying drawing shows dia- 45 grammatically, by way of example, one form of construction according to this in- vention.

In the drawings, 1 denotes the crane jib, pivoting at 2 on a frame suitably mounted on the deck or a platform. On either side of 50 pivot 2, and in a plane containing the longitudinal axis of the jib, are arranged similar luffing screws 3, 4, working in opposite directions, one for pulling and the other for pushing, by means of which the jib 1 can 55 be luffed from a position indicated in full lines to another position, for example that shown in broken lines.

When this device is employed, the force necessary for luffing the jib and its load does 60 not act on the pivot 2, for it comprises two equal forces acting in opposite directions on either side of the pivot. The total force expended is the same as that in known systems, which have a luffing screw on one side 65 only of the pivot, while the length of the screw is reduced to about half.

Having now particularly described and ascertained the nature of my said invention and in what manner the same is to be per- 70 formed, I declare that what I claim is:

1. In a luffing crane, a crane support, a jib pivoted on a horizontal axis on said support, and two luffing screws for said jib, arranged one on either side of the crane, in 75 a plane containing the longitudinal axis of the crane, said screws acting in opposite directions.

2. In a luffing crane, a crane support, a jib pivoted on a horizontal axis on said sup- 80 port, and two luffing screws for said jib, said screws being of equal length and ar- ranged one on either side of the crane, in a plane containing the longitudinal axis of the crane, said screws acting in opposite direc- 85 tions.

In testimony whereof I affix my signature in presence of two witnesses.

FRANS SMULDERS.
